CLAIM

The ornamental design for a scissors handle, as shown and described.

DESCRIPTION

FIG. 1 is a front elevational view of a scissors handle showing my new design in a closed condition;

FIG. 2 is a rear elevational view;

FIG. 3 is a top plan view;

FIG. 4 is a bottom plan view;

FIG. 5 is a left side elevational view;

FIG. 6 is a right side elevational view;

FIG. 7 is a front elevational view in an open condition; and,

FIG. 8 is a rear elevational view of FIG. 7.

The blades depicted by means of broken lines in FIGS. 1 and 2 have been shown for illustrative purposes only and form no part of the claimed design.
